UNITED STATES PATENT OFFICE.

FRANKLIN W. BROOKS, OF WASHINGTON, DISTRICT OF COLUMBIA.

SEAL-PRESS.

SPECIFICATION forming part of Letters Patent No. 650,807, dated May 29, 1900.

Application filed January 12, 1900. Serial No. 1,217. (No model.)

To all whom it may concern:

Be it known that I, FRANKLIN W. BROOKS, a citizen of the United States, residing at Washington city, in the District of Columbia, have invented certain new and useful Improvements in Seal-Presses; and I do hereby declare the following to be a full, clear, and exact description of the invention, such as will enable others skilled in the art to which it appertains to make and use the same.

My invention relates to certain new and useful improvements in seal-presses, and particularly to that class in which a pawl-and-ratchet mechanism is employed to secure complete and uniform impression of the seals subjected to the action of the dies.

In presses as originally constructed the dies were made to approach each other through the medium of lever-handles, having free vibratory movement in either direction, and consequently the impressions produced were, according to the resistance offered by the seal or the carelessness of the operator, not uniform and frequently indistinct. To obviate this difficulty, presses were constructed involving the use of pawl-and-ratchet mechanism in connection with the vibrating handle-lever in order that after the handle is started in the direction necessary to cause the approach of the dies the handle is prevented from reversing its movement until it has first completed the sealing movement, and consequently the dies necessarily approach each other to precisely the same degree in each instance, resulting of necessity in uniformity of impression upon seals successively submitted to the action of the dies. An early instance of the mechanical construction controlling the movement of the lever-handle and movable die is illustrated and described in the expired Letters Patent No. 152,081, granted June 16, 1874, to Joseph Corbett, assignor to The Railway Register Manufacturing Company of Buffalo, New York.

As before stated, my invention relates to that class of sealing-presses which involve the employment of a pawl-and-ratchet mechanism for controlling the action of the movable handle-lever and die, and has for its object to provide a press of this character which shall be economic and durable in construction, which shall be comparatively light,

easily manipulated, and which shall also secure at all times and under all conditions the proper presentation of the seal between the 55 impression-dies; and with these ends in view my invention consists in the features of construction hereinafter fully set forth and claimed.

In order that those skilled in the art to 60 which my invention appertains may know how to make and use the same, I will proceed to describe the construction and operation, referring by letters to the accompanying drawings, in which—

Figure 1 is a front view showing the head of the press with a peculiarly-constructed seal entrance or gateway. Fig. 2 is a vertical section taken on the line *x x* of Fig. 5. Fig. 3 is a similar section taken on the line *y y* of Fig. 1 and showing the relation of the pawl-and-ratchet devices in the position assumed when the movable handle-lever is nearing its extreme outward or opening throw. Fig. 4 is a similar view, but showing the relation of the pawl-and-ratchet devices when the lever-handle had completed its inward or closing movement and has caused the pawl to be released from the ratchet, so that the handle-lever can be opened toward the position shown at Fig. 3. Fig. 5 is a central longitudinal section on the line *z z* of Fig. 1. Fig. 6 is a detail perspective view of the spring employed for raising the movable die and assisting in the opening movement of the 75 lever-handle. Fig. 7 is a perspective view of the lower stationary adjustable cup-die and showing its circumferential wall cut away to register with the seal entrance or gateway in the head of the press, and Fig. 8 is a side 80 view of a seal for which the press is adapted. Fig. 9 is a detail view of the movable die.

Similar letters of reference indicate like parts in the several figures of the drawings.

A and B represent the handles of the press, and for convenience in the description I will 95 denominate the former as the "movable" handle and the latter as the "stationary" handle.

The stationary handle B is formed with a head C, having two upwardly-projecting cheeks D D, between which the movable handle is pivoted by a bolt or pin E. The head C is bored centrally to receive the movable reciprocating die F and the lower adjustable

cup-die G. These dies may be introduced either through the upper or lower end of the bore or channel referred to. The lower end of this channel is formed with a female thread 5 to receive a screw-threaded adjusting-plug H, which constitutes a seat or anvil for the cup-die G, as clearly shown at Fig. 5, and by reason of the adjustability of the plug H it will be obvious that the cup-die G may be adjusted 10 with reference to the movable die F so that seals of different thickness may be operated upon with equal pressure and like results as to the characters impressed thereon. When the proper vertical adjustment of the 15 cup-die and plug has been made, the cup-die is adjusted axially, so that the cut-away portion I of its projecting or circumferential wall J will register with the seal entrance or gateway K in the head of the press, whereupon it is secured against accidental movement by 20 a set-screw L, and the plug H is also secured by a similar set-screw M.

The lower die in the instance illustrated in the drawings is cup-shaped on its upper face, 25 adapting it to the particular seal for which it is designed and which consists of a lower sheet-metal cup embracing a lead body with an upwardly-projecting rivet or hat-shaped head, as shown at Fig. 8, corresponding in 30 shape and dimension with the upper portion of the gateway or entrance K in the head of the press.

By reference to Fig. 8 and the seal entrance or gateway K (best shown at Fig. 1) 35 it will be seen that the seal can only enter the gateway when presented in a position corresponding with the shape and proportions of the gateway, and consequently the sheet-metal cup rests upon the lower die G, and 40 the hat-shaped head of the lead portion is crushed and impressed by the movable die F.

The upper or movable die is held in proper axial position and is raised by a flat spring N, one end of which enters a radial slot or 45 pocket in the die, as clearly shown at Fig. 5, and the opposite end of which is secured to the stationary handle B by a suitable screw O.

The movable handle is formed with a cam-shaped face adapted to contact with the upper end of the movable die F, as clearly shown 50 at Fig. 5, so that when the said handle approaches the stationary handle B the die F will be forced downwardly toward the cup-die G, and consequently the seal is compressed 55 between the two dies to lock the shackle-wire, and at the same time any suitable characters upon the face of the movable die are impressed upon the seal to the same extent and uniformly.

60 The spring N, as before stated, retracts the movable die when the movable handle is released and assists in an obvious manner to lift the said handle.

P is a stud or screw inserted in the lower 65 stationary handle B to constitute a stop and to limit the closing movement of the movable handle A.

The front or cam-shaped head portion of the handle A is provided on each side with a ratchet Q of the design and construction 70 clearly shown at Figs. 3 and 4. These ratchets are preferably formed separately from the handle and are secured in place by rivets or rods R, or in any other suitable manner, or, if thought desirable, they may be made integral 75 with the handle.

The ratchet-teeth are concentric with the axis of the handle A and terminate at the lower extremity in a projecting nose or lip S and at the upper extremity in a curved face 80 T, for the purposes presently explained. The ratchet-teeth of the two ratchets Q are so arranged relatively to each other that the teeth of one ratchet will be in the same plane as the spaces of the other, so that the two pawls 85 presently described will act alternately, and for the purpose of preserving the effectiveness of the pawl-and-ratchet mechanism, even though one of said pawls or ratchets should become disabled or inoperative, and at the 90 same time if both are operative, presenting a double security against the return movement of the handle until a proper impression has been made upon the seal.

U U are two pawls secured vibratively to 95 the two cheeks D of the head of the lower handle B by pivots V. These pawls are of the design shown, with a V-shaped projection W, adapted to interlock successively with the teeth of the ratchets Q and to contact at the 100 proper time with the nose or lip S of the ratchets, as shown at Fig. 3, or with the curved face thereof, as shown at Fig. 4. The tail of the pawls are formed with two notches or seats a b to receive the free end of a flat spring 105 X, which is secured to the lower stationary handle B by the same screw which secures the spring N in place, as clearly shown in Fig. 5. When the free end of the pawl-spring X is in the seat b the V-shaped projection W 110 of the pawl is held in contact with the ratchet-teeth of the ratchet Q, as shown at Fig. 3, and when said spring is in the seat a the pawl is held out of contact and in the position shown at Fig. 4. These two described positions of 115 the spring X with reference to the pawls are controlled in the following manner, to wit: When the movable handle A has been closed to the proper extent to secure the complete compression of the seal and the proper impression upon the same of the characters on the face of the die or dies, the curved faces 120 T of the ratchets will contact with the V-shaped projection W of the pawls and vibrate the same rearward, as shown at Fig. 4, causing 125 the free end of the pawl-spring X to enter the seats a, and thus hold the V-shaped projection W out of contact with the ratchets Q and permitting the handle to be opened to the position shown at Fig. 3, when the noses S of 130 the ratchets contact with the V-shaped projections of the pawls U, vibrating them into the position shown to interlock successively with the ratchet-teeth, or, in other words,

restores them to their normal operative positions.

While I have shown the lower stationary cup-die with a concave upper face to produce a convex form of the sheet-metal portion of the seal illustrated at Fig. 8, it will be understood that the face of said die may be of any other form and may be adapted to impress any desired characters upon a seal composed wholly of lead or other suitable metal, and while the seal shown in elevation at Fig. 8 is of a particular configuration and proportions corresponding with a similarly designed and proportioned seal entrance or gateway in the head of the press I do not wish to be limited in this respect, but desire it to be understood that my invention in this particular rests in the broad idea of providing the head of the press with a seal entrance or gateway of such form with reference to the seal intended for use therewith that the seal can be introduced to the action of the dies in one position only, thus securing with absolute uniformity the impressions of the dies always upon the same sides or faces of the seals. I desire to call especial attention to the form and construction of the cup-shaped stationary die. I have already explained the manner of adjusting and securing it and the movable die in position, and it will therefore be obvious that both dies may be readily removed and others substituted therefor, according to the diameter of the seal or variety of impressions that it may be desirable to impress upon such seals, and as it is desirable that such impressions should always be properly located with reference to the boundaries or circumference of the seal the upwardly-projecting circumferential wall J constitutes a means for securing this object, because it serves to center and properly locate the seal for which it is especially designed, while if the said wall was absent the walls of the seal-channel in the head of the press would constitute the only stop or adjustment of the seal, and obviously a small seal would enter the gateway to a further extent than a larger one and consequently the characters impressed by the dies

would be eccentric. The adjustability of the lower or cup die is also important in order that seals of varying thickness may have a predetermined or equal degree of pressure exerted upon them to secure the proper degree of sharpness in the impressions made and to compensate for wear. I make the head of the screw-plug H of hemispherical or equivalent form to prevent the press from being used, as they frequently are, as a hammer, which results not infrequently in the destruction or impairment of the press.

Having described the construction, operation, and advantages of my improved press, what I claim as new, and desire to secure by Letters Patent, is—

1. In a seal-press, the combination of two lever-handles, a movable die, and a stationary die, a ratchet connected with each side of the head of the movable handle and terminating in a lip S, and curved face T, spring-paws pivoted to the stationary handle and provided with a V-shaped projection W, and notches a, b, and a spring X, substantially as and for the purpose set forth.

2. In a seal-press, the combination of a movable and a stationary handle, a movable die, and an adjustable stationary die seated within the head of the stationary handle, means independent of the adjustable die for vertically adjusting the same and means substantially as described for securing the said die against axial relation, as and for the purpose set forth.

3. In a seal-press, a movable and a stationary handle, compression-dies and a gateway or entrance in the head of the press and leading to the space between the dies, said gateway being of varying widths at different localities and conforming to the design of the seal, whereby the latter can be presented in one way only.

In testimony whereof I affix my signature in presence of two witnesses.

FRANKLIN W. BROOKS.
